UNITED STATES PATENT OFFICE.

CHARLES E. BEARDSLEY AND ALVA T. SMITH, OF WATERBURY, CONNECTICUT, AS-SIGNORS, BY MESNE ASSIGNMENTS, TO THE BEARDSLEY AND WOLCOTT MANUFACTURING COMPANY, OF WATERBURY, CONNECTICUT, A CORPORATION OF CONNECTICUT.

COMBINATION LAMP AND SMOKER'S STAND.

Application filed November 21, 1927. Serial No. 234,597.

This invention relates to lamp stands, and more particularly to a lamp stand having a horizontal support for a smoker's stand extending forwardly from its base.

5 One object of this invention is to provide a device of this nature, in which the support for the smokers's stand is recessed for fitting about the base thereof.

10 A further object is to provide a device of this nature which will be simple in construction, inexpensive to manufacture, easy to manipulate, ornamental in appearance, and very efficient and durable in use.

15 With these and other objects in view there has been illustrated on the accompanying drawing one form in which the invention may be conveniently embodied in practice.

20 Fig. 1 represents a side view of the lamp stand and smoker's stand in assembled position.

Fig. 2 is a perspective view of the bottom portion of the lamp stand showing its forwardly extending recessed base.

25 Referring now to the drawings in which like reference numerals denote corresponding parts throughout the several views, the numeral 10 indicates a hollow column adapted to receive an electrical conductor 11 for supplying current to the lamp. The 30 top of the column is provided with an ornamental bridge arm 12 which is also preferably made hollow for receiving the electrical conductor 11. The forward end of the bridge arm 12 is bent downwardly and 35 connected to a lamp socket 13 which is adapted to be operated by a push switch 14 and having the usual shade 15 depending therefrom.

40 In order to enhance the artistic appearance of the lamp stand, the column 10 is provided at its top with an ornamental capital 16 and has a central ornamental collar 17 and a bottom ornamental pedestal 18. The ornamental pedestal 18 is adapted to rest 45 upon a rear semi-circular portion 19 of a flat base plate 20, said base plate 20 having an

enlarged forwardly extending portion 21, herein shown as octagonal in shape. The forward portion 21 of the base plate 20 is provided on its top face with a circular 50 ornamental upstanding bead or rim 22 having a rounded outer edge. The bead 22 has a vertical interior edge 23 which is adapted to fit snugly about a circular base 24 of a 55 smoker's stand 25.

The recess formed in the forward portion 21 of the base plate 20 within the bead 22 is provided with ornamental figures 26 so that the base of the lamp stand will present a 60 pleasing appearance when the smoker's 65 stand 24 is not in position therein.

It will thus be seen that a combination lamp and smoker's stand has been provided wherein the smoker's stand may be detachably held in the lamp stand in position to be 65 conveniently accessible to a person who is 70 sitting adjacent the lamp for reading or other purposes.

While there has been disclosed in this specification one form in which the invention 75 may be embodied, it is to be understood that this form is shown for the purpose of illustration only, and that the invention is not to be limited to the specific disclosure but may be modified and embodied in various other forms without departing from its 80 spirit. In short, the invention includes all the modifications and embodiments coming within the scope of the following claims.

Having thus fully described the invention, what is claimed as new, and for which it is desired to secure Letters Patent, is:

1. In an article of furniture, a hollow column for carrying electric conductors, a hollow lamp-holding bridge arm mounted 85 on said column, a flat base for said column adapted to rest upon the floor, said base having an enlarged forwardly-extending section having a recess in its upper face, and a smoker's stand having a base fitted into 90 said recess for preventing lateral movement of said stand relative to said base when said

base is carried about, the top of said stand being located in a position accessible to the person using the lamp.

2. In an article of furniture, a column having lifting means at the upper end thereof, said column being supported by a flat base adapted to rest upon the floor, said base having an enlarged forwardly extend-

ing section provided with an upstanding rim, and a smoker's stand having a base shaped to fit within said rim, said rim serving to retain said stand in position. 10

In testimony whereof, we have affixed our signatures to this specification.

CHARLES E. BEARDSLEY.
ALVA T. SMITH.
